ELECTRIC CONTROL BOX

Leslie S. Thomas, Orchard Lake, Mich., assignor to General Motors Corporation, Detroit, Mich., a corporation of Delaware

Filed Oct. 24, 1958, Ser. No. 769,384

3 Claims. (Cl. 200—50)

This invention relates to electrical control boxes and more particularly to a control box having a safety linkage between the main latch mechanism and the switch operating mechanism to eliminate some of the dangers which arise due to the unauthorized personnel entering the control box.

In most installations making use of electrical control boxes, such as fuse boxes, or switch boxes of some type, there is always the danger of unauthorized personnel entering the box and the possibility of accidents resulting therefrom. In order to compensate for these dangers, it has been the practice in the past to provide some sort of switch actuating mechanism which is directly connected to the door latch mechanism such that the switch is automatically shut off when the door is opened. This type of control box, however, gives a great amount of difficulty when maintenance on the switch means, or other electrical equipment within the box, becomes necessary. Skilled maintenance personnel, in order to repair the contents of the box, must be able to actuate the switch when the door is open. If the switch control is interlocked to the door actuating mechanism for the safety of unauthorized personnel it may be seen that maintenance on the equipment may be made only when the door is open and the switch in the open or off position.

The other possibility, in order to compensate for this disadvantage, is to have a switch actuating mechanism that is in no way connected or controlled by the door latch mechanism. This possibility, however, is poor from a safety standpoint, due to the inherent dangers of the switch being closed when the door is in an open position.

The device in which this invention is embodied comprises three interconnected mechanisms, a main door latch mechanism, a switch actuating mechanism, and a connecting mechanism between the door latch and switch actuation. With this control box it is possible to actuate the switch mechanism by the door latch structure whereby closing the door will require a second operation to actuate the switch. However, the door normally may be opened unless the switch is first opened, that is, in the off position. In order for maintenance personnel to enter the box while the switch is in a closed position, a defeater mechanism is provided which disconnects the connecting mechanism from the switch actuating mechanism to allow the maintenance operator to open the door without opening the switch. The defeater mechanism is so arranged that inexperienced or unauthorized personnel could not open the box without a special tool, and thus would be protected from unauthorized entry.

Thus, a control box is provided having numerous safety features, the main feature being the possibility of skilled personnel entering the box for proper maintenance purposes and at the same time eliminating the dangers inherent in unauthorized personnel entering the control box. The device is relatively simple to operate and inexpensive to manufacture. Existing control boxes could be modified according to the invention without exorbitant cost, thus

2

making an industry wide safety feature available to most all installations.

In the drawings:

Figure 1 is an isometric view of the control box embodying this invention with the door shown in an open position to illustrate the location and relationship of the various parts.

Figure 2 is an elevational view of the control box with the door in phantom and the actuating mechanisms shown in full lines to illustrate the location and relationship of the parts when the door is in a closed position.

Figure 3 is a sectional view of a portion of the control box shown in Figure 2, taken substantially along the line 3—3 and looking in the direction of the arrows.

Figure 4 is a sectional view of a portion of the control box shown in Figure 2, taken substantially along the line 4—4 and looking in the direction of the arrows.

Figure 5 is a sectional view of a portion of the control box shown in Figure 2, taken substantially along the line 5—5 and looking in the direction of the arrows.

Referring more particularly to the drawings, Figures 1 and 2 best show the over all control box and interconnected linkages. The control box itself comprises top and bottom panels 10 and 12, side panels 14 and 16, and a back panel 18. A flanged rim 20 extends around the periphery of the open side of the box to provide a dirt seal and tamper proof closure surface for the door 22. The door may be hinged to either of the side panels 14 or 16 in any suitable manner, such as by a piano type hinge or a plurality of strap or butt hinges. The door 22 has a flange 24 surrounding the periphery and facing inwardly to overlie the flange 20 formed on the control box.

A switch 26 is mounted in the box, preferably adjacent the corner formed by the side plate 14 and the top plate 10, and serves to control any type of electrical system, not shown, which may be located in the lower portion of the box. A switch handle 28, rotatably secured in the switch 26 and pivoted on the shaft 30, actuates the switch 26 to open or close the usual contacts.

The main door latch mechanism is operated by a handle 32 disposed on the outer surface of the door 22. A shaft 34 extends through the door panel 22, through a spacer member 36, and supports the lower latch cam 38. The latch cam is provided with a knife edge 40, and it may be seen from viewing Figures 1 and 2 that rotation of the handle 32 will rotate the latch cam 38 to carry the knife edge 40 behind the flanged portion 20 of the control box when the door is closed. The lower latch cam 38 is secured for rotation with the shaft 34 by the set screw 42.

An upper cam 44 of the same configuration as the lower cam 38 is rotatably secured to the inner side of the door panel 22 by the flanged spacer member 46 and the shaft 48. The upper latch cam 44 may be secured to the shaft 48 in any convenient manner as by a washer 50 held in place by a conventional cotter pin 52.

A connecting rod 54 is pivotally secured to the upper and lower cams as at 56 and 58 and serves to rotate the upper and lower latch cams in unison. Rotation of the handle 32 and the lower latch cam 38 will lift the connecting rod 54, which rotates the upper cam 44. A compression spring 60, acting between a tab 62 secured to the connecting rod 54 and a tab 64 secured to the inner surface of the door panel 22, biases the connecting rod, and consequently the latch cams, in the lower or opening position, the position shown in Figure 1.

The switch actuating mechanism includes a plate 66 having the apertures 68 and 70 formed therein. A bracket member 72, or a plurality thereof, extends from the plate 66 inwardly of the box and is pivoted from the back panel 18 as by the pivot shaft 74. The bracket

member 72 may be welded to the plate 66 such that the plate 66 is pivotally movable with respect to the switch plate 26. The switch handle 28 extends through the aperture 68 in the plate 66 and movement of the plate about the pivot point 74 will open or close the switch 26.

A pair of bearings 76 are secured to the inner surface of the door panel 22, as by bolts 78, and are vertically spaced thereon. A switch actuating rod 80 is vertically movable in the bearings 76 and has attached thereto the hinged switch actuating links 82 and 84, pivotally connected as by the pin 86. The link member 84 extends through the aperture 70 in the plate 66 and it may be seen that vertical movement of the rod 80 will rotate the plate 66 through the links 82 and 84 to actuate the switch handle 28.

A tab 88, having a slot 90 formed therein, is secured to the upper portion of the connecting rod 80 and provides the actuator means for connecting rod. A switch actuating handle 92, located on the outer surface of the door panel 22, extends through an opening 94 in the panel and is secured to the rotating bracket plate 96 by the bolts 98. Rotation of the handle 92 will rotate the bracket plate 96 inside the door panel 22. A pin 100 is secured in the rotating bracket plate 96 and extends into the slot 90 in the tab 88. It is obvious that rotation of the handle 92 will thus actuate the rod 80, the links 82 and 84 and the plate 66 to open or close the usual contacts in the switch 26.

The defeater mechanism is actuated by a pin 102 which extends through the door panel 22 and through a bearing 104. The pin 102 is secured in a plate 106 adjacent the inner surface of the door 22, the connection being such that rotation of the pin 102 will rotate the plate 106. The pin 102 is illustrated as having a slot in the outer end, allowing the pin 102 and the plate 106 to be turned by a conventional screwdriver. However, to prevent unauthorized personnel from operating the mechanism, the pin 102 may have some special configuration in the end to permit operation only by a special tool. A tab 108 secured to the door panel 22 and a compression spring 110 abutting the plate 106, resiliently biases the plate 106 in the position shown in Figures 1 and 2. The purpose of a push bar 112 rigidly secured to the plate 106 and the notch 114 formed in the plate will be later described.

Preliminary latching means are provided for the door 22 by a hook member 116, secured to the plate 106, and the preliminary latch bar 118, secured in any convenient manner in the control box. The hook member 116 has a shoulder 120 formed thereon and an inclined surface 122 between the end of the hook member and the shoulder 120. A complementary inclined surface 124 is provided on the end of the preliminary latch member 118. It may be seen that by closing the door 22 the surfaces 122 and 124 will allow the hook member to slide past the end of the preliminary latch member 118, and the shoulder 120 to engage the end of the latch member 118. Thus, the door is retained in a partially closed position, the opening being such that there is no danger to personnel operating the box. The switch actuator mechanism may then be operated to close the switch 26.

Secured to the connecting rod 54 of the main door latch mechanism is a link 126 which extends toward the center of the door. An arcuate cam surface 128 is formed in the end of the member 126. A second link 130 is pivotally secured to the first link member 126 by a pivot pin 132. The joining surface of the link 130 is complementary to the cam surface 128 of the first link member 126, the member 130 having a stop shoulder 134 adapted to abut the edge of the first link member 126 such that rotation past the shoulder is not possible. The links are biased into the position shown by the torsion spring 136 acting on the buttons 138. The position just described is as illustrated in Figures 1 and 2.

The pivot pin 132 connecting the links 126 and 130, has an extension 140, best seen in Figure 3, extending through the link members 126 and 128 and is adapted to be received in the notch 114 formed in the plate 106.

A stop tab 142 is secured to the switch actuating rod 80 and cooperates with the tip 144 of the link member 130. The purpose of the abutment will be later described.

The operation of the control box is as follows: With the door 22 open, the parts are in the position shown in Figure 1. When it is desired to close the door and actuate the switch 26, the operator swings the door until the preliminary latch hook 116 engages the latch bar 118. The latch handle 32 is then rotated to engage the latch cams 38 and 44 with the edge 22 of the control box. As the latch cam 38 is rotated and connecting rod 54 raised, the links 126 and 130 also move vertically upwardly with the connecting rod 54 and the extension 140 of the pin 132 engages the inclined surface 146 of the plate member 106. The plate member 106 rotates against the pressure of the spring 110, releasing the preliminary latch means and allowing the door to be fully closed. The extension 140 is received in the notch 114 in the plate 106 and the spring 110 returns the plate 106 to its normal position. The parts are then as shown in full lines in Figure 2.

The switch actuating handle 92 may then be turned from outside the box to close the switch 26, rotation of the handle 92 rotating the bracket plate 96 and raising the switch actuating rod 80, through the tab 88. The pivoted links 82 and 84, extending through the aperture 70 in the plate 66, rotate the plate 66 about the pivot point 74 to actuate the switch handle 28 and close the switch 26. At this time the stop tab 142 on the switch actuating rod 80 is raised into abutment with the end 144 of the connecting link 130. The parts are then as shown in dashed and dotted lines in Figure 2.

The control box is thus operational, the door being closed and the switch 26 actuated, and the box may remain as such for as long as necessary.

When it is desired that the control box be opened the handle 92 is rotated to rotate the plate 66 and the switch handle 28 to open the switch 26. The stop tab 142 drops with the connecting rod 80 and out of the way of the link 130. A screw driver, or other convenient tool, is used to rotate the defeater pin 102, thus rotating the plate 106 and freeing the extension 140 of the pin 132 from the notch 114 of the plate 106. The handle 32 is forcibly rotated by spring 60 to disengage the latch cams 38 and 44 from the side flange 20, allowing the door to be opened.

If the operator should wish to open the door without opening the switch 26 he may do so by leaving the switch actuating handle 92 in the switch-on position and rotating the pin 102 and the defeater plate 106. The push bar 112 rotates the connecting link member 130 out of engagement with the stop tab 142 and at the same time frees the extension 140 of the pin 132 from the notch 114. The door actuator handle 132 is forcibly rotated by spring 60 to free the latch connections 38 and 44 from the side flange. The operator then has access to the box with the switch in the closed position.

If the door has not been latched when the switch 26 is actuated, tab 142 on the rod 80 will engage the shoulder 144 on the ring member 130, thus raising the ring members 130 and 126, lifting the latch mechanism and securing the latch cams 38 and 48 behind the flange 20 of the box.

Thus it may be seen that a control box is provided which allows access thereto only by a skilled operator, and preventing entrance by unauthorized personnel. The control box door may be opened with the switch either in the on or off position at the desire of the operator, it being assumed that the person opening the door is skilled

enough to know whether or not the switch should be on or off.

I claim:

1. An electric control box comprising a plurality of panels defining an open sided box, a switch secured in said box, a door hingedly secured at one edge to one of said panels, a latch handle rotatably secured to the outside of said door and having a shaft extending through said door, a first latch cam secured to said shaft and rotatable with said handle, a second latch cam rotatably secured to said door and spaced from said first latch cam, a connecting rod pivotally secured to said first and second latch cams to rotate said second cam in conjunction with said first cam when said first cam is rotated by said handle and secure said door to said box in a closed position, switch actuating means secured to said door and vertically movable with respect thereto, means pivotally secured to said switch and within said box and engaged by said switch actuating means to open and close said switch when rotated by said switch actuating means, connecting means operable between said switch actuating means and said connecting rod to actuate said switch actuating means and open said switch when said connecting rod and said latch cams are disengaged from said box to open said door, and independently operated defeater means to disengage said connecting means and actuate said connecting rod and said latch cams to open said door without actuating said switch actuating means and to allow access to said switch and said box when said switch is in a closed position.

2. An electric control box comprising a plurality of panels defining an open sided box, a switch secured to a portion of said panels and within said box defined thereby, and having a switch handle extending therefrom, a door hingedly secured at one edge to one of said panels, latch means rotatably secured to said door and engaging another of said panels to retain said door in a closed position, a bar pivotally secured to said switch within said box and having spaced apertures therein, one of said apertures engaging said switch handle for actuation thereof, a rod secured to said door and vertically movable with respect thereto, link means secured to said rod and movable therewith and extending through another of said

apertures to raise and lower said bar and said switch handle to actuate said switch, connecting means operable between said latch means and said rod to move said rod and said bar and said switch handle and open said switch when said latch means are operated to open said door, and independently operated defeater means engaging said connecting means to disengage said connecting means and actuate said latch means for opening said door without actuating said switch and allow access to said switch and said box when said switch is closed.

3. An electric control box comprising a plurality of panels defining an open sided box, a switch secured to a portion of said panels and within said box, a door hingedly secured at one edge thereof to one of said panels, latch means rotatably secured to said door and engaging another of said panels to secure said door in a closed position, switch actuating means secured to said door and vertically movable with respect thereto, means pivotally secured to said switch and within said box and engaged by said switch actuating means to open and close said switch when rotated by said switch actuating means, a connecting link operable between said switch actuating means and said latch means to actuate said switch actuating means and open said switch when said latch means are operated to open said door, a defeater plate pivotally secured to said door and having a notch formed therein to retain said latch means in a closed position, said defeater plate being rotatable to release said latch means and allow said latch means to disengage from said box for opening of said door, and a push bar secured to said defeater plate and rotatable therewith to disengage said connecting link from said switch actuating means when said plate is rotated to disengage said latch means and prevent said connecting link from actuating said switch actuating means and opening said switch when said latch means disengages from said box and said door is opened.
